UNITED STATES PATENT OFFICE

OLIVER SMITH, OF OAKLAND, CALIFORNIA, ASSIGNOR OF TWO-THIRDS TO EUGENE Z. SCHULER AND JAMES E. MCDONALD, BOTH OF OAKLAND, CALIFORNIA

DESIGN FOR A GLARE SHIELD FOR AUTOMOBILES

Application filed February 5, 1930. Serial No. 34,410. Term of patent 14 years.

To all whom it may concern:

Be it known that I, OLIVER SMITH, a citizen of the United States, residing at Oakland, in the county of Alameda and State of California, have invented a new, original, and ornamental Design for Glare Shield for Automobiles, of which the following is a specification, reference being had to the accompanying drawing, forming part hereof.

In the drawing, Figure 1 is a plan view and Figure 2 is a longitudinal sectional view showing my new design of a glare shield for automobiles.

I claim:

The ornamental design for a glare shield for automobiles as shown.

OLIVER SMITH.
